UNITED STATES PATENT OFFICE.

HOWARD E. MARSH, OF LOMPOC, CALIFORNIA.

SELF-FEEDING CARBURETOR.

Application filed August 10, 1925. Serial No. 49,351.

This invention relates to self feeding carburetors of the type disclosed in my prior Patent No. 1,553,453, issued September 15th, 1925, and an object of the invention, in general, is to effect automatic feeding of liquid fuel to the carburetor from a lower level without it being necessary to employ the customary vacuum tank.

Another object is to provide a construction in which it is unnecessary to employ a needle valve operated by the float, thus avoiding troubles that arise from the use of a needle valve as, for example, in seating properly because of wear or fouling.

Another object is to provide a construction in which two chambers are required instead of three as in the prior patented carburetor mentioned above.

Another object is to avoid a reduction of pressure behind the fuel as it is drawn by the engine suction into the mixing chamber.

A further object is to provide novel means for controlling the flow of fuel into the mixing chamber.

Other objects and advantages will appear in the subjoined detailed description.

The accompanying drawings illustrate the invention:

Fig. 1 is a plan view of self feeding carburetor constructed in accordance with the provisions of this invention.

Fig. 2 is a sectional elevation on the line indicated by 2-2, Fig. 1.

Fig. 3 is an enlarged fragmental section on the line indicated by 3-3, Fig. 1.

Fig. 4 is an enlarged fragmental plan section on the irregular line indicated by 4-4, Fig. 2.

Two chambers are provided, a chamber 5 and a chamber 6. In this instance, the chamber 6 is positioned inside of the chamber 5 and concentric therewith, being provided at its upper end with an outwardly projecting flange 7 which rests upon the upper edge of the chamber 5 and is clamped between said upper edge and a cover 8. The cover 8 is secured in place by screws or other fastenings 9 and is provided with a fuel inlet 64 adapted for connection by a fuel pipe, not shown, with a source of fuel supply. The chamber 5 is the supply chamber for fuel and is provided in its bottom with a drain cock 10 and near the top with a port 65 that opens to the atmosphere. The chamber 6 is the float chamber containing a float

11 of suitable construction as, for example, of hollow metal construction. Secured to the bottom of the chamber 6 and projecting upwardly therein is guide member 12 which is accommodated in a vertical hole 13 in the float 11 so as to guide the float as it rises and falls and prevent it from engaging the side walls of the chamber 6 or assuming a level position when the carburetor 65 is tilted.

The float is provided on its top with a slotted member 14, the slot 15 therein being vertical and being engaged by one of the arms of a bell crank lever 16 which is fulcrumed at 17 on a bracket 18 that projects downwardly from the cover 8. Thus, when the cover is removed, the lever 16 comes with it. The other arm of the lever 16 projects through an opening 19 in the cover 8 and into a valve chamber 20 that, in this instance, is formed in the cover. This other arm of the lever 16 engages in a vertical slot 21 of an ear 22 that projects from a cylindrical valve 23 provided in its periphery with an annular groove or port 24. The valve chamber 20 has a removable head 25 that is screwed into place.

The chamber 20 is provided in its top with a suction port 26 that extends through a boss 27 provided with threads so that it may be connected by a union, not shown, to the intake manifold of the engine with which the carburetor functions. The valve chamber 20 is provided in its bottom with a pair 90 of ports 28, 29 which communicate with the float chamber 6. The port 28 is a suction port for exhausting air from the float chamber 6 and is in alignment with the port 26 and, accordingly, the port 24 will register simultaneously with the ports 26, 28 when the valve is moved sufficiently far to the right in Fig. 2 by appropriate drop of the float 11. When the float rises above the position shown in Fig. 2 it moves the valve 23 to the left so as to simultaneously register the port 24 with the port 29 and with a port 30 that is vertically aligned with the port 29 and that opens laterally from the valve chamber 20 and communicates with the atmosphere.

The bottom of the chamber 6 is provided with a port or ports 31 communicating with the chamber 5, there being a check flap valve 32 movably mounted in the chamber 5 to prevent, when closed, flow of fuel from the chamber 5 through the ports 31 into the

chamber 6 and to admit, when open, of flow of fuel from the chamber 6 through the ports 31 into the chamber 5. The valve 32 is pivoted at 33 to a lever 34 that, preferably, is 5 weighted at 35 on its outer end so that said lever will function to yieldingly hold the valve 32 closed when the pressures in the chambers 5, 6 are equal. The lever 34 is fulcrumed at 36 to a bracket 37 projecting 10 downwardly from the bottom of the chamber 6. The valve 32 is guided by a stem 38 that projects into a vertical guideway 39 formed in the lower end of the member 12.

The wall of the chamber 5 is sufficiently 15 thick at one place to form a valve chamber 40, the inner face of the wall of the chamber 40 being formed by a circular sleeve 41 provided with a longitudinally extending slot 42 that preferably expands outwardly so 20 that foreign substances that may be in the fuel will not stick fast in the slot. The sleeve is held from turning by a pin 67. Communicating with the slot 42 is a nozzle slot duct or orifice 43 that opens into the 25 mixing chamber 44 of the carburetor. Inserted in the sleeve 41 and slidable therein is a cylindrical valve 45 provided in its periphery with a projection 46 that slides in the slot 42 so as to prevent turning of the 30 valve 45 in the sleeve when a stem 47, that is screw threaded into the valve 45, is rotated. The stem 47 projects through a head 48 that closes one end of the valve chamber 40, the other end of said valve chamber being closed by a head 49. The projecting 35 end of the stem 47 is provided with an arm 50 by which said stem is turned so as to cause the valve 45 to move endwise to cover more or less of the nozzle duct 43, thus to regulate 40 the flow of fuel from the valve chamber 40 to the mixing chamber 44. The closing movement of the valve 45 is limited by a stop in the form of a screw 66 that projects from the head 49 into the chamber 40 so that 45 one end of the valve 45 will strike the stop 66 while a portion of the slot 42 is open sufficiently for idling of the engine.

The fuel enters the valve chamber 40 50 through a duct 51 that leads from said chamber to the lower portion of the chamber 5. In order that the fuel admitted to one end of the chamber 40 from the duct 51 can pass through the valve 45 to the other 55 end of said chamber said valve is provided with a longitudinally extending duct or ducts 52.

The passage 53 to the mixing chamber 44 60 is provided with a butterfly valve 54 and the passage 55 leading from the mixing chamber 44 is provided with a butterfly valve 56. The valve 54 is operated by an arm 57 and the valve 56 is operated by an arm 58. In this instance, I connect the arms 57, 58 by a 65 link 59 that is pivoted at 60, 61 to said arms, respectively. Also, in this instance, the arm

50 is connected by a link 62 with the arm 57 and link 59, the pivot 59 also passing through the link 62 and a pivot 63 connecting the links 62 with the arm 50. The arms 50, 57, 58 and the links 59, 62 are so proportioned and arranged as to produce the desired relative degree of opening of the valves 45, 54, 56 to economize in the use of the fuel. 70

It being assumed that the fuel intake 64 is connected with a fuel tank placed at a lower 75 level than the carburetor and that the port 26 is connected with the intake manifold of the internal combustion motor with which the carburetor functions, the operation of the carburetor above described is as follows: 80

If the carburetor is empty when the connection is made with the fuel tank, the float 11 will be in its lowermost position and the check valve 32 will be closed. When the float 11 is in its lowermost position, and the motor is started in the usual manner, the valve 23 will be in position to register its port 24 with the ports 26, 28, thus creating a partial vacuum in the chamber 6. This, as is readily understood, causes the fuel to flow into the float chamber and the float to rise. As the float rises it moves the port 24 out of registration with the ports 26, 28, but the inward flow of fuel continues because of the continued partial vacuum in the float 90 chamber. When the float 11 reaches a predetermined level, the valve 23 has been actuated into a position to register the port 24 with the ports 29, 30, thus admitting atmospheric air to the float so as to break the vacuum, and, accordingly, stop the inward flow 100 of fuel. This breaking of the vacuum will occur when the level of fuel in the chamber 5 is slightly below the outlet end of the nozzle duct when the engine is not in operation, thus preventing flooding of the carburetor at such time. As the engine operates, the liquid 105 level in the chamber 5 varies very little because as soon as fuel is drawn from the chamber 5, the valve 32 will open, permitting fuel to flow from the float chamber 6 into the chamber 5. As the fuel is drawn from the float chamber, the float 11 will lower, thus again placing the chamber 6 in communication with the intake manifold of the engine 110 so that a partial vacuum will be created in the float chamber and thus cause the inflow of fuel to the float chamber as before.

When higher speed of the engine is desired, the arm 50 will be turned to cause the 115 movement of the valve 45 in a direction to open to a wider extent the nozzle duct 43.

From the foregoing it will be readily understood that the carburetor is of comparatively simple construction, employing but 120 few parts and operating in an efficient manner so as to obtain the proper mixture of fuel and air required by the engine under different load conditions.

The various valves described above may 130

be constructed differently than described so long as they function properly to produce the desired results but I prefer to employ the construction described for the valve that 5 controls the flow of fuel into the mixing chamber because of its nicety of positive adjustment.

It will be noted that, because of the presence of the check valve for preventing back- 10 flow of fuel into the chamber 6, partial vacuum produced in the float chamber cannot tend to lower the liquid level in the chamber 5 to lessen the pressure behind the fuel as it is drawn by the engine suction into the 15 mixing chamber.

I claim:

A self feeding carburetor comprising a mixing chamber, a fuel supply chamber communicating with the mixing chamber, 20 and opening to the atmosphere, a float cham-

ber having a port opening into the fuel supply chamber, said float chamber provided with a constantly open fuel inlet, a check valve to prevent flow of fuel from the fuel supply chamber through the port, a float in 25 the float chamber, a valve chamber having a suction port and having an air admission port communicating with the atmosphere, the float chamber provided with ports aligned with the suction and air admission ports 30 respectively, a cylindrical valve having a single port, and means operated by falling of the float to move the valve into position to register its port with the suction port and operated by rising of the float to move the 35 valve into position to register its port with the air admission port.

Signed at Los Angeles, California, this 5th day of August, 1925.

HOWARD E. MARSH.
